[57] CLAIM

The ornamental design for a revolver barrel, as shown.

DESCRIPTION

FIG. 1 is a side elevational view of a revolver barrel, showing my new design.

FIG. 2 is a front elevational view.

FIG. 3 is a top plan view.

FIG. 4 is a rear elevational view; and

FIG. 5 is a bottom plan view.

FIG. 6 is a side elevational view of another embodiment of revolver barrel of my invention.

FIG. 7 is a front elevational view of FIG. 6.

FIG. 8 is a top plan view of FIG. 6.

FIG. 9 is a rear elevational view of FIG. 6; and

FIG. 10 is a bottom plan view of FIG. 6.
